UNITED STATES PATENT OFFICE.

WILLIAM S. JACKSON, OF VEEDERSBURG, INDIANA.

MOLD-SUPPORT.

No. 807,935.

Specification of Letters Patent.

Patented Dec. 19, 1905.

Application filed February 18, 1905. Serial No. 246,300.

To all whom it may concern:

Be it known that I, WILLIAM S. JACKSON, a citizen of the United States, residing at Veedersburg, in the county of Fountain and State 5 of Indiana, have invented new and useful Improvements in Mold-Supports, of which the following is a specification.

This invention relates to mold-supports such as are used particularly in supporting 10 molds or forms for sewers, concrete arches, and the like.

The objects of the invention are to improve and simplify the construction of such devices; furthermore, to increase their efficiency in 15 operation and to decrease the expense attending their manufacture.

With the foregoing and other objects in view, which will appear as the description proceeds, the invention resides in the arrangement of parts and the details of construction 20 hereinafter described and claimed as a practical embodiment thereof.

In the accompanying drawings, forming part of this specification, Figure 1 is a trans- 25 verse section through a sewer or concrete arch, illustrating a convenient method of employing the improved mold-support of this invention. Fig. 2 is a longitudinal section through the structure illustrated in Fig. 1. 30 Fig. 3 is a detail perspective view of one of the brackets.

The reference character *a* indicates a body of cement or other suitable material, which is supported in the form of an arch by means 35 of a suitable mold or form. The mold or form may be of any suitable form and construction. In the structure illustrated in the drawings the form comprises a plurality of planks *a'*, such as are usually employed in 40 forming structures of this character.

The improvements of the present invention relate particularly to the means for supporting the mold, which is formed by the planks *a'*. To this end the invention comprises a 45 pair of brackets A B. As shown in Fig. 3, each of the brackets preferably is formed with a mold-supporting member 1, which is shaped to conform to the character of mold employed. In the embodiment of invention 50 illustrated in the drawings a semicircular mold is employed. For this reason the mold-supporting member 1 of each bracket is shaped on the quarter of a circle. In addition to the mold-supporting member 1 each 55 of the brackets also comprises what I shall

for convenience term a "common" member 2. Diverging from the common member 2 on an angle slightly greater than a right angle is a pair of arms 3 4, which are connected at their separated ends with the mold-supporting 60 member 1. The arm 3 is formed with a laterally-offset portion 5 adjacent to the mold-supporting member 1 for a purpose hereinafter to be described. Arranged between the arms 3 and 4 is a plurality of intermediate arms 6 7, 65 which diverge from the common member 2 to the mold-supporting member 1, as shown clearly in Fig. 3.

In forming an arch or sewer according to the present invention the improved mold-supporting brackets are used in pairs, as illustrated in Figs. 1 and 2, the laterally-offset portions 5 of the two brackets being arranged adjacent to each other. Means are employed for separating the upper ends of the two 70 brackets. While any suitable means—such, for example, as a wedge or block—may be used for this purpose, it is preferred to use a turnbuckle having saddle members 8 and 8, which straddle the laterally-offset portions 5 of the 75 brackets A and B, as shown in Fig. 1. By manipulating the turnbuckle in the proper manner it will be apparent that the brackets will be forced into the proper position to support the mold, which is formed by the planks 80 *a'*. In order that the two brackets may be easily removed when necessary, it is preferable to support the common member 2 of each bracket upon a block 9, which may rest upon the ground or upon a suitable support 10, resting at its ends upon thickened planks *a''*, arranged at the bottom of the mold. The blocks 9 may be easily knocked away in order to permit the removal of the brackets. 85

The construction of the improved mold-support of this invention is such that by loosening the separating device C after the cement *a* has become sufficiently hard the brackets A and B can be readily removed to permit the removal of the mold, which is formed by the 90 planks *a'*.

Changes in the precise embodiment of invention illustrated and described may be made within the scope of the following claims without departing from the spirit of the invention 105 or sacrificing any of its advantages.

Having thus described the invention, what is claimed as new is—

1. A mold-support comprising a bracket having a mold-supporting member shaped on 110

a quarter of a circle, a common member, a pair of arms diverging from said common member to said supporting member on an angle slightly greater than a right angle, one of said arms having a laterally-offset portion adjacent to the mold-supporting member, and intermediate arms diverging from the common member to the mold-supporting member.

- 5 2. A mold-support comprising a pair of brackets each having a mold-supporting member, a common member and a pair of arms diverging from said common member to said mold-supporting member, and adjustable separating means disposed between said brackets.
- 15 3. A mold-support comprising a pair of brackets each having a mold-supporting member, a common member, a pair of arms diverging from said common member to said mold-supporting member, one of said arms having a laterally-offset portion adjacent to the mold-supporting member and a separating device
- 20

contacting with the laterally-offset portions of the two brackets.

4. A mold-support comprising a pair of brackets each having a mold-supporting member shaped on a quarter of a circle, a common member, a pair of arms diverging from said common member to said mold-supporting member on an angle slightly greater than a right angle, one of said arms having a laterally-offset portion adjacent to the mold-supporting member, and intermediate arms diverging from the common member to the mold-supporting member, and a turnbuckle having saddled members contacting with the laterally-offset portions of the two brackets.

25 30 35 In testimony whereof I affix my signature in presence of two witnesses.

WILLIAM S. JACKSON.
